ZBOM Urban Pastoral Kitchen reference found online [Dec. 14, 2018]—http://www.zbomcabinets.com/article_read_46.html.*Primary Examiner — Lakiya G Rogers*Assistant Examiner* — John A Voytek(74) Attorney, Agent, or Firm — JCIPRNET(57) CLAIM

The ornamental design for a set of kitchen cabinets, as shown and described.

DESCRIPTION

FIG. 1 is a perspective view of a set of kitchen cabinets showing our new design;

FIG. 2 is another perspective view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

A rear view is omitted since it does not contain ornamental features.
